(57) **CLAIM**

The ornamental design for a light emitting diode treatment device, as shown and described.

DESCRIPTION

FIG. 1 is a top perspective view showing the light emitting diode treatment device of the present invention;

FIG. 2 is a bottom perspective view thereof;

FIG. 3 is a top plan view thereof;

FIG. 4 is a side view thereof;

FIG. 5 is a bottom plan view thereof;

FIG. 6 is a front view thereof; and,

FIG. 7 is a rear view thereof.

The broken line showing parts of the drawings is included for the purpose of illustrating use and environment and forms no part of the claimed design.
